UNITED STATES PATENT OFFICE.

HECTOR ANTOINE BERGERON, OF MONTREAL, QUEBEC, CANADA.

FURNACE.

1,220,312.

Specification of Letters Patent.

Patented Mar. 27, 1917.

Application filed June 22, 1916. Serial No. 105,198.

To all whom it may concern:

Be it known that I, HECTOR ANTOINE BERGERON, a subject of the King of Great Britain, residing in the city of Montreal, in the Province of Quebec, in the Dominion of Canada, have invented certain new and useful Improvements in Furnaces; and I do hereby declare that the following is a full, clear, and exact description of same.

10 The invention relates to improvements in a furnace, for supplying hot water or steam and the object of the invention is to secure greater efficiency and simplicity of the construction.

15 In order to obtain these results, specially designed water sections are provided, consisting of a plurality of cup-shaped sections superposed over one another and connected centrally and a main pipe leading outside 20 of the furnace, the lower ends of said cup-shaped sections being connected to a suitable water supply. Within or below the lower section is provided a fire pot, gas jet or any other suitable means of heating the 25 same, the heated fumes circulating within each section by means of openings provided therein.

The following is a description of the illustrations in which Figure 1 is a front elevation view of the furnace.

Fig. 2 is a perpendicular cross section of the furnace.

Fig. 3 is a cross section view on lines A—A of Fig. 2.

5 Fig. 4 is a cross section view on lines B—B of Fig. 2.

Like numerals of reference indicate corresponding parts in each figure.

In the drawings, 1 is a casing, 2 is the top portion preferably bolted to said casing 1, at 3 by means of the bolt 4 and 5 is a base here shown constructed of cement.

6 is a base plate provided over said base 5 and 7 is a reservoir which may be of any size or shape, but here shown as circular. Petroleum or any other suitable oil, whether crude or refined, may be used in said reservoir 7 and 8 is a pipe leading from the said reservoir 7 to the center of the furnace and 9 is a burner secured on said pipe 8.

10 is an opening provided through the side of the casing 1, in order to reach the burner 9, and 10^a is a door to close said opening.

The casing 1 is provided with a plate 11 which is preferably slanted inwardly in the

shape of a funnel, said plate 11 being provided with openings 12 and 13 are air openings or vents provided in said plate at different intervals.

14 is the inner section or smallest section 60 provided with a water circulation there-around and 15 is a header connected on top of said section 14.

16 is a cup-shaped section placed over said section 14 and connected to the header 15 65 by means of the nipple 17, said section 16 being secured above said plate 11 so as to leave a sufficient space for the fumes to circulate around the cup-shaped section 18, which is connected to said section 16 by means of 70 a nipple 19. The said section 18 rests on the plate 11 and is provided at its top portion with openings or passages 20 for the fumes to reach the cup-shaped section 21, which is connected to said section 18 by means of 75 the nipple 22 said cup-shaped section 21 being slightly elevated over plate 11 so as to form a passage 23 for the fumes, which coming through the opening 20, will naturally be forced to pass through said opening 23 80 into the chamber 24 and through the exhaust pipes 25 which are provided on top of said top section 2.

26 is a pipe secured on top of said section 21 leading through said top section 2 to any 85 suitable distribution chamber.

The oil in the reservoir 7 is preferably compressed by means of a pump, (not shown in the drawings) and by doing so a more active combustion will be obtained thus forcing 90 the fumes through the top of the section 14 into the compartment provided between the said section 14 and the section 16. The fumes or gases coming through the outlet in the said section 16 will be ignited as they 95 pass through said outlet in coming in contact with the oxygen which will penetrate through the outlets 13 thus providing another center of combustion. The gases escaping from this second combustion will 100 escape through the opening 20 provided on top of the section 18 into the chamber of the section 21 and they will also naturally be forced through the opening 23 and again will ignite in coming in contact with the 105 oxygen coming through the opening 13, and the gases produced by this third combustion will escape through the outlets 25. It will thus be seen that all the gases that can be burnt will be utilized in producing the maxi- 110

2
mum heat as only the non-combustible gases will escape through the outlets 25.

27 is a main water supply pipe provided with the branches 28 leading from said main pipe and connected to the bottom or lower part of the sections 14, 16, 18, and 21.

It may be here stated that any other suitable means of combustion can be used in this improved furnace without departing from the spirit of the invention. For instance in place of using oil or gas to produce heat, an ordinary coal fire can be provided inside section 14 to produce heat, and the gases escaping through its combustion can give the same results.

Steam as well as hot water can be produced by this furnace in which the main idea resides in the plurality of cup-shaped sections, overlapping one another so that the 20 gases resulting from combustion will completely inclose the said section before they reach their outlet, and also provide means to ignite these gases at different intervals in order to produce new centers of combustion 25 and thereby obtain the maximum heat from the combustible gases.

What I claim is:—

1. A furnace comprising a casing, a plurality of cup shape sections overlapping one another and suitably connected together with said casing, passages provided between said sections for the circulation of the heated fumes, water inlets and water outlets provided in said sections, a base plate secured within said casing and below said sections provided with vent holes or pas-

sages and means to heat said sections substantially as described.

2. A furnace comprising a casing, a base plate suitably supported within said casing, 40 a plurality of cup shape sections overlapping one another and suitably connected together, every second section being shorter than the other in order to form a passage between said sections and said base plate, 45 and passages provided in the uppermost part of the first and third sections, means to supply said sections with water, and means to heat said sections substantially as described.

3. A furnace comprising a casing, provided with fumes outlets, a base plate suitably supported within said casing provided at intervals with a plurality of vent holes, a plurality of cup shape sections overlapping 55 one another and suitably connected together, passages provided between said sections for the circulation of the heated fumes, water supplying means connected to one end of said sections and means to conduct the hot 60 water or steam from said sections, an oil reservoir provided below said base plate, a burner suitably connected to said reservoir, said burner being suitably disposed centrally of the inner section substantially as de- 65 scribed.

Signed at Montreal, Quebec, Canada, this 30th day of May, 1916.

HECTOR ANTOINE BERGERON.
